Phineas H. York,

By Offield, Dowd & Cutticom,

Atto.

UNITED STATES PATENT OFFICE.

PHINEAS H. YORK, OF CHICAGO, ILLINOIS, ASSIGNOR TO THE TONK MANUFACTURING COMPANY, OF SAME PLACE.

DESIGN FOR A PEDESTAL FOR PIANO-STOOLS.

SPECIFICATION forming part of Design No. 28,030, dated December 14, 1897.

Application filed November 1, 1897. Serial No. 657,109. Term of patent 7 years.

To all whom it may concern:

Be it known that I, PHINEAS H. YORK, a citizen of the United States, residing at Chicago, in the county of Cook and State of Illinois, have invented and produced a new and original Design for Pedestals for Piano-Stools, of which the following is a specification, reference being had to the accompanying drawing, which shows a perspective view of a piano-stool embodying my design.

The leading feature of my design consists in a pedestal consisting of a circular cap-piece and a cruciform base provided with feet, a central fluted column with molded cap and base interposed between the center of the cap-piece and base, and other fluted columns of like design interposed between the arms of the cruciform base and the circular cap-piece, being thus grouped around the central column.

A indicates the cap-piece, which is circular in form and has a molded or otherwise ornamented edge.

B indicates the base, which is cruciform in shape, provided with the feet b, and has interposed between it and the cap-piece A the central fluted column C and the fluted columns D, four in number, grouped around the central column and extending from the ends of the arms of the base to the cap-piece.

30

I claim—

The design for a pedestal for piano-stools, substantially as herein shown and described.

PHINEAS H. YORK.
